RAILWAY SWITCH OPERATING APPARATUS

Herbert L. Bone, Pittsburgh, Pa., assignor to The Union Switch & Signal Company, Swissvale, Pa., a corporation of Pennsylvania

Application October 14, 1933, Serial No. 693,626

16 Claims. (Cl. 246—318)

My invention relates to railway switch operating apparatus, and particularly to apparatus for operating spring switches.

One object of my invention is to provide apparatus of the type described including means for locking the switch in both extreme positions in such manner that if a train trails the switch in either extreme position, the switch will become automatically unlocked by means mechanically actuated by the wheels of the train, and will remain unlocked until the train is completely past the switch, after which the switch will again become locked in the extreme position which it previously occupied.

Other objects of my invention will become apparent as the description proceeds.

I will describe two forms of apparatus embodying my invention, and will then point out the novel features thereof in claims.

In the accompanying drawings, Fig. 1 is a top plan view showing a spring switch A controlled by a switch operating and locking mechanism B constructed in accordance with my invention. Fig. 2 is an enlarged transverse sectional view of the connecting rod C forming part of the apparatus illustrated in Fig. 1. Fig. 3 is an enlarged top plan view of the switch operating and locking mechanism B shown in Fig. 1 with the parts in their normal positions, the circuit controller and the cover for the main part of the mechanism being removed to better illustrate the construction of the mechanism. Fig. 4 is a longitudinal sectional view of the mechanism shown in Fig. 3. Fig. 5 is a view, similar to Fig. 3, but showing the parts of the mechanism in their reverse positions. Fig. 6 is a diagrammatic view showing the spring switch A operated by means of a lever located at a remote point and provided with a modified form of lock mechanism, which lock mechanism also embodies my invention.

Similar reference characters refer to similar parts in each of the several views.

Referring first to Fig. 1, the reference character A designates a railway switch comprising, as usual, two fixed rails 1 and 1^a and two movable rails 2 and 2^a. The fixed rails 1 and 1^a are laid on tie plates 3 and are secured to cross-ties 4 in the usual manner. The movable rails 2 and 2^a are fastened together by a front rod 5, a head rod 6, a bridle rod 7 and a tie rod 8, and may be moved into a normal or a reverse position by means of a switch operating mechanism B which is connected with the head rod 6 through the medium of an operating rod 9 and

a spring connecting rod C. When the switch occupies its normal position in which position it is shown in Fig. 1, the movable rail 2 engages the fixed rail 1, and the movable rail 2^a is spaced a slight distance from the fixed rail 1. When the switch is reversed, however, the movable rail 2^a then engages the fixed rail 1^a, and the movable rail 2 is spaced from the fixed rail 1.

The spring connecting rod C may have any suitable form, but in the well-known form here illustrated, this connecting rod comprises a cylindrical housing 10 having a lateral extension 10^a fastened to the head rod 6 (see Fig. 2). The lower end 10^b of the housing 10 has a smaller diameter than the body of the housing, while the upper end is threaded to receive a cap 11 having an end 11^a similar to the end 10^b. Slidably mounted in the opening in the end 10^b is a sleeve 12 provided with an annular flange 12^a located within the housing 10, and similarly mounted in the opening in the end 11^a is a sleeve 13 provided with an annular flange 13^a which is also located within the housing 10. A spring rod 14 extends through the sleeves 12 and 13 with sufficient clearance to permit the rod to slide freely in the sleeves, and this rod carries a compression spring 15 which engages the sleeves at their annular flanges and urges the sleeves toward the positions in which the annular flange 12^a of the sleeve 12 engages the shoulder formed on the inside of the housing 10 by the end 10^b, and the annular flange 13^a of the sleeve 13 engages the shoulder formed on the inside of the cap 11 by the end 11^a. The spring rod 14 is provided with an annular shoulder 14^a for at times engaging the outer end of the sleeve 12, and with a nut 14^b for at times engaging the outer end of the sleeve 13. The lower end of the spring rod 14 is pivotally attached to the operating rod 9. The operation of the spring connecting rod C is well understood and need not, therefore, be described here.

The head rod 6 is also connected by means of an adjustable link 16 with the piston rod 17 of a buffering device D. This buffering device may be of any suitable type, but as here shown, this buffering device is similar in all respects to the buffering device shown and described in Letters Patent of the United States No. 1,869,604, granted to William C. McWhirter, August 2, 1932, for Buffering devices for railway switches and the like. It is believed, therefore, that for purposes of the present disclosure the following brief description of the buffering device D will suffice. This buffering device includes in addition to the piston

rod 17, a cam shaft 18 extending into the case of the device and controlling a valve mechanism not shown. Attached to the outer end of the cam shaft 18 is a crank 19 which is connected by a link 20 with the spring rod 14 of the spring connecting rod C. If, when the movable rails 2 and 2^a of the switch A are in their normal positions, as shown in Fig. 1, they are moved to their reverse positions by the mechanism B, the piston rod 17 will be moved into the device, and the cam shaft 18 will be rotated in a clockwise direction, as viewed from the left in Fig. 1. The construction of the device is such that, under these conditions, the piston rod 17 will be permitted to move with substantially no resistance, and the buffing device will therefore exert practically no retarding action on the movable rails. Conversely, if the movable rails are moved from their reverse positions to their normal positions by the mechanism B, the piston rod 17 will be moved outwardly and the cam shaft 18 will be rotated in a counter-clockwise direction, as viewed from the left in Fig. 1, but due to the construction of the device no retarding action will again take place. If, however, when the movable rails are in either extreme position, a train trails the switch, the cam shaft 18 will remain stationary, and, under these conditions, the action of the device is such that the movement of the movable rails away from the positions which they previously occupied will be unresisted by the buffing device, but that, when the movable rails are being restored to the positions which they previously occupied by the spring 15 of the spring connecting rod C, the buffing device will act to retard this latter movement.

The switch operating mechanism B is mounted on one end of a tie strap 21 which is secured to the outer side of the rail 1, and as best seen in Fig. 4, this mechanism comprises a main casing 22 and an auxiliary casing 23 which is secured to the left-hand end of the main casing 22. The upper end of the main casing 22 is closed by a removable cover 24 while the upper end of the auxiliary casing is closed by a removable cover 25.

Formed in the main casing 22 is an axially extending rectangular guideway 22^a which slidably receives a motion plate 26. The motion plate 26 is provided on its upper face with rack teeth 27 and on its lower face with a cam slot 28, and is adapted to be reciprocated between two extreme positions by means of a hand throw lever 30 fixed to a shaft 31. The shaft 31 is journaled in suitable bearings 32 formed in the sides of the casing 22, and has fixed thereto a segment of gear 33 which meshes with the rack teeth 27. As best seen in Fig. 3, the cam slot 28 is formed with a portion at each end which is parallel to the direction of movement of the motion plate, and with an intermediate connecting portion which is disposed at an angle to the direction of movement of the motion plate. Extending into the cam slot 28 and cooperating therewith is a roller 34 which is mounted on a pin 35 secured to an arm 36 forming part of a crank 31. The crank 31 is journaled in a vertical bearing 38 provided in the bottom of the casing 22 and has fixed thereto, on the underside of the casing, a removable switch operating arm 39 which is pivotally attached to the free end of the connecting rod 9.

Reciprocably mounted in the casing 22 directly above the motion plate 26 is a locking device 40 comprising two parallel spaced end

members 40^a and 40^b secured together by means of two spaced bolt members 40^c and 40^d. The bolt member 40^c extends with considerable clearance through aligned holes 41^a and 41^b formed respectively in two upstanding lugs 42^a and 42^b provided on the upper face of the motion plate 26, and has disposed thereon a coil spring 43^a. One end of this coil spring bears against an inwardly extending flange 44^a forming part of a spring socket 45^a which is slidably mounted in the hole 41^a in the lug 42^a, and the other end of this spring bears against an inwardly extending annular flange 44^b forming part of a spring socket 45^b which is slidably mounted in the hole 41^b in the lug 42^b. The bolt member 40^d likewise extends with considerable clearance through aligned holes 41^c and 41^d formed respectively in two upstanding lugs 42^c and 42^d provided on the upper face of the motion plate 26, and has disposed thereon a coil spring 43^b, one end of which bears against an inwardly extending annular flange 44^c forming part of a spring socket 45^c which is slidably mounted in the hole 41^c in the lug 42^c, and the other end of which bears against an inwardly extending annular flange 44^d forming part of a spring socket 45^d which is slidably mounted in the hole 41^d in the lug 42^d. Each spring socket 45 is free to slide on the associated bolt member, and is provided at the end opposite to the inwardly extending annular flange, that is, at its open end, with an outwardly extending annular flange designated by the reference character 46 with the same distinguishing exponent as the exponent for the reference character of the associated spring socket. The outwardly extending annular flanges on the spring sockets cooperate with the associated lugs in a manner which will be made clear as the description proceeds.

Attached to the end member 40^a is an integral rectangular locking plunger 47. This locking plunger projects with some clearance into a longitudinally extending slot 48 formed in the left-hand end of the casing 22 and is provided with two locking dogs 47^a and 47^b (see Fig. 4). The locking dog 47^a cooperates with a pair of aligned notches 49 formed in a lock rod L which is slidably mounted in a transverse slot 50 provided in the casing 22, and the locking dog 47^b likewise cooperates with a pair of aligned notches 51 formed in the lock rod L. As here shown, the lock rod L is of standard construction, and comprises two longitudinally adjustable bars 52 and 53 attached at one end to the front rod 5 of the switch A in the usual and well-known manner.

The notches 49 in the lock rod L are so disposed that these notches will align with the locking dog 47^a when and only when the switch occupies its extreme normal position; and the parts are so proportioned that when the notches 49 are in alignment with the locking dog 47^a, if the motion plate 26 then occupies its extreme left-hand position in which it is shown in Figs. 3 and 4, the lugs 42^b and 42^d on the motion plate will engage the spring sockets 45^b and 45^d at the flanges 46^b and 46^d, and will thus exert a force on the locking device through the medium of the spring sockets 45^b and 45^d, the springs 43^a and 43^b, the spring sockets 45^a and 45^c and the end member 40^a, which force will move the locking device toward the left to a position in which the locking dog 47^a enters the notches 49, thereby securely locking the switch in its normal position. Furthermore, the notches 51 in the lock rod L are so disposed that these notches

will align with the locking dog 47^a when and only when the switch occupies its extreme reverse position, and the parts are so proportioned that when the notches 51 are in alignment with the locking dog 47^b, if the motion plate then occupies its extreme right-hand position in which it is shown in Fig. 5, the lugs 42^a and 42^c will then engage the spring sockets 45^a and 45^b at the flanges 46^a and 46^c, and will thus exert a

force on the locking device through the medium of the spring sockets 45^a and 45^b, the springs 43^a and 43^b, the spring sockets 45^b and 45^d and the end member 40^d, which force will move the locking device toward the right to a position in which the locking dog 47^d enters the notches 51.

The locking device 40, in addition to being operatively connected with the motion plate 26 by means of the lugs 42, the spring sockets 45 and the springs 43 in the manner just described, is operatively connected with the previously described tie rod 8 by means of linkage which I will now describe.

As here shown, this linkage includes a plunger bolt 54 which extends with some clearance through a centrally located hole 40^e formed in the end member 40^e of the locking device 40, and the head of which bolt cooperates with the left-hand side of the end member, as viewed in Figs. 3 and 4. The bolt 54 is relatively long, and secured to the bolt a predetermined distance from its head is a collar 54^a which cooperates with the right-hand end of the end member 40^b in a manner which will be described hereinafter. The threaded end of the plunger bolt 54 is adjustably connected by means of a turnbuckle 55 (see Fig. 1) with one end of a link 56, the opposite end of which link is pivotally connected with the long arm 57^a of a bell crank lever 57. The bell crank lever 57 is pivotally supported in a crank stand 58, and has its short arm 57^b pivotally connected with one end of an operating rod 59. The other end of the operating rod 59 is connected with the previously described tie rod 8 by means of a standard switch basket 60.

For reasons which will be made clear as the description proceeds, the extreme position to which the locking device 40 is movable when the notches 49 in the lock rod L are in alignment with the locking dog 47^a and the motion plate 26 occupies its extreme left-hand position is beyond the desired locking position, and the linkage connecting the locking device with the tie rod 8 is so adjusted that when the switch occupies its extreme normal position, the head of the plunger bolt 54 will engage the end member 40^b of the locking device and will prevent the locking device from moving beyond the desired locking position, which position I will term its "normal" locking position. Likewise, the extreme position to which the locking device 40 is movable, when the notches 51 in the lock rod L are in alignment with the locking dog 47^b and the motion plate 26 occupies its right-hand extreme position, is beyond the desired locking position under these latter conditions, and the collar 54^a is so positioned on the plunger bolt 54 that when the switch occupies its extreme reverse position, the collar 54^a will engage the end member 40^b of the locking device and will prevent the locking device from moving beyond the desired locking position, the desired locking position under these latter conditions hereinafter being referred to as the "reverse" locking position.

The tie rod 8 may be located at any suitable location, but will preferably be located approx-

imately half way between the heel and the point of the switch. The base 61 of the crank stand 58 is secured to a gage plate 62 which, in turn, is secured to the tie strap 21 upon which the mechanism B is mounted, and it will be apparent, therefore, that any loss of adjustment between the parts due to creepage of the ties is prevented.

The operation, as a whole, of the portion of the apparatus thus far described is as follows:

When the hand throw lever 30 occupies the extreme position in which it is shown in Figs. 1 and 3, the motion plate 26 is held in its extreme left-hand or normal position as viewed in Figs. 3 and 4, and the roller 34 on the crank 37 then occupies the right-hand end of the cam slot 28 in the motion plate, so that the crank 37 is held at the extreme end of its stroke in a clockwise direction, as viewed in Figs. 1 and 3. When the crank 37 occupies this extreme position, a force is exerted on the movable rails 2 and 2^a of the switch through the medium of the operating rod 9, spring rod 16, nut 14^b, sleeve 13, spring 15, housing 10 and the head rod 6, which force holds the movable rails in their normal extreme positions in which they are shown in Fig. 1. When the movable rails are in their normal positions, the notches 49 in the lock rod L align with the locking dog 47^a, and the locking device 40 is therefore moved by the biasing springs 43 to its "normal" locking position in which the locking dog 47^a partly enters the registering notches 49, thus securely locking the movable rails of the switch in their normal positions.

When it is desired to reverse the switch, the hand throw lever 30 is rotated from the extreme position in which it is shown in Fig. 3, to the extreme position in which it is shown in Fig. 5. This movement of the lever 30 causes the motion plate 26 to move from its extreme left-hand position to its extreme right-hand position. At the beginning of this movement, due to the fact that when the switch occupies its normal position, the locking device 40 is prevented from moving to its extreme left-hand position by the linkage which connects the locking device with the tie rod 8, the flanges 44^a and 44^c on the closed ends of the spring sockets 45^a and 45^c are in engagement with the end member 40^a of the locking device 40, and the flanges 46^a and 46^c on the open ends of these spring sockets are spaced some distance to the right of the lugs 42^a and 42^c on the motion plate 26, while the flanges 46^b and 46^d on the open ends of the spring sockets 45^b and 45^d are in engagement with the lugs 42^b and 42^d, and the flanges 44^b and 44^d on the closed ends of these spring sockets are spaced the same distance from the end member 40^d that the flanges 46^a and 46^b are spaced to the right of the lugs 42^a and 42^c. It will be seen, therefore, that during that part of the movement of the motion plate toward the right which is necessary to move the lugs 42^a and 42^b on the motion plate into engagement with the flanges 46^a and 46^b, the springs 43^a and 43^b will move the spring sockets 45^b and 45^d toward the right to the positions in which the flanges 44^b and 44^d on these spring sockets engage the end member 40^b, but no movement of the locking device 40 will take place. As soon, however, as the lugs 42^a and 42^b have moved into engagement with the flanges 46^a and 46^c on the spring sockets 45^a and 45^c, any further movement of the motion plate will cause the locking device to move with the motion plate, and as a result, as the motion plate continues to move, the locking dog 47^a will be withdrawn from

the notches 49 in the lock rod L, thus unlocking the switch. The parts are so proportioned that while the locking dog 47^a is being withdrawn from engagement with the notches 49 in the lock rod L, the cam slot 28 in the motion plate 26 will 5 continue to engage the roller 34 on the crank 37 at that portion of the right hand end of the cam slot which is parallel to the direction of movement of the motion plate, and as long as this portion of the slot is engaging the roller, the crank 10 37 will remain stationary. It follows, therefore, that during that portion of the movement of the motion plate which is necessary to unlock the movable rails of the switch, no force is exerted 15 on these rails tending to reverse them. As soon, however, as this part of the movement of the motion plate has been completed, the roller 34 is then engaged by the curved portion of the cam slot 28 which causes the crank 37 to be 20 rotated in a counter-clockwise direction, as viewed in Fig. 3, and as a result, the movable rails are then moved to their reverse positions. As previously pointed out, when the movable rails are moved to their reverse positions by the 25 mechanism B, the piston rod 17 of the buffering device D is moved into the device, and the cam shaft 18 is rotated in a clockwise direction, as viewed from the left in Fig. 1, but due to the construction of this device, the device offers substantially 30 no resistance to the movement of the movable rails under these conditions. It should be noted that as long as the movable rails remain stationary, the plunger bolt 54 remains fixed, so that during that part of the movement of the motion plate necessary to unlock the 35 switch, the end member 40^b of the locking device 40 will move out of engagement with the head of the plunger bolt. As soon as the movable rails have started to move, however, the 40 resultant movement of the tie rod 8 acting through the switch basket 60, operating rod 59, bell crank lever 57, and link 56 will cause the motion plate 54 to move in the same direction as the plunger bolt is moving, although the time 45 of motion and rate of motion of the plunger bolt will bear no direct relation to the movement of the motion plate. As soon as the movable rails have been moved to their full reverse positions, the cam slot 28 then engages the roller 34 at that 50 portion of the slot at its left-hand end which is parallel to the direction of movement of the motion plate, and no further movement of the crank 37 takes place. The movement of the movable rails to their reverse positions, of course, 55 moves the lock rod L upwardly as viewed in Fig. 1 to the position in which the notches 51 in the lock rod align with the locking dog 47^b, and as the lock motion plate continues its movement, the locking dog 47^b enters the notches 51, thus locking 60 the switch in its reverse position. Shortly before the motion plate reaches the end of its stroke, the end member 40^b moves into engagement with the collar 54^a on the plunger bolt 54, which stops the locking device in its reverse locking position, and during the balance of the movement of the motion plate, the springs 43^a and 43^b become compressed, the parts finally assuming the positions in which they are shown in Fig. 5.

In order to restore the movable rails to their 70 normal positions after they have been reversed as above described, the lever 30 is restored to the position in which it is shown in Fig. 3. The subsequent movements of the parts, under these conditions, are just the reverse of those described 75 above, and it is believed, therefore, that the

operation of the apparatus under these conditions will be readily understood from the foregoing and from an inspection of the drawings without further description.

I will now assume that the parts are in their normal positions, as shown in Figs. 1, 3 and 4, and that a train trails the switch. As the leading wheels of the train roll along the fixed rail 1 and the movable rail 2^a, the movable rails 2 and 2^a are forced over laterally, but, before a sufficient 10 force is developed to overcome the opposing force of the spring 15 of the spring connecting rod C and cause the point of the movable rail 2 to move out of engagement with fixed rail 1, the movable rails, being somewhat resilient, become bent, so 15 that with the usual standard split switch, the tie rod 8 is moved upwardly, as viewed in Fig. 1, three-quarters of an inch or more. This movement of the tie rod 8 acting through the switch basket 60, operating rod 59, bell crank lever 57, link 56 and plunger bolt 54 moves the locking device 40 in opposition to the bias of the springs 43 a sufficient amount to withdraw the locking dog 47^a completely out of engagement with the notches 49 in the lock rod L, thus unlocking the 20 switch. As a result, when the leading wheels have reached the position in which a sufficient force is developed to cause the point of the movable rail 2 to move out of engagement with the fixed rail 1, the movable rails will be unlocked, 25 and these rails will therefore be forced open by the wheels in exactly the same manner as would be the case if no point lock were provided, and the buffering device D will perform its usual function of preventing the rails from snapping back 30 after the passage of the wheels through them. After the train which is trailing the switch has completely passed the switch, the movable rails will slowly return to their normal positions under the bias of the spring 15 of the spring connecting rod C, and against the retarding force of the buffering device D. During this return movement of the movable rails there will be no deflection of these rails, and the locking dog 47^a will 35 be moved into engagement with the lock rod L 45 before the movable rails have reached their full 50 normal positions in which the lock rod is in the proper position for the notches 49 therein to receive the locking dog. The springs 43 will therefore become compressed and will urge the locking dog 47^a into engagement with the side of the lock rod until the notches 49 move into alignment with the locking dog, at which time the energy stored in the compressed springs 43 will 55 force the locking dog into place in the notches, thus restoring the switch to its normal locked condition.

When the parts occupy their reverse positions and a train trails the switch, the lateral bending of the movable rails which takes place before 60 a sufficient force is developed at the points of these rails to overcome the opposing force of the spring 15 of the spring connecting rod C and cause the movable rail 2^a to move out of engagement with the fixed rail 1^a will cause the tie 65 rod 8 to move downwardly, and this movement of the tie rod will act through the switch basket 60, operating rod 59, bell crank lever 57, link 56, the shank of the plunger bolt 54, and the collar 54^a on the plunger bolt 54 to move the locking device 40 toward the left in opposition to the bias of the springs 43 far enough to withdraw the locking dog 47^b out of engagement with the notches 51 in the lock rod, thus unlocking the switch. After the movable rails of the switch 75

become unlocked in this manner, they will be forced away from their reverse positions by the wheels of the train in the same manner as if no point lock were provided and will be prevented from snapping back between the passage of the successive wheels of the train by the buffering device D. When the train has completely passed the switch, the spring connecting rod C will slowly return the rails to their reverse positions, thus restoring the lock rod L to the position in which the notches 51 align with the locking dog 47^b and hence permitting the springs 43 to restore the locking device to its reverse locking position in which the locking dog 47^b re-enters the notches 51 and relocks the rails in their reverse positions.

During a facing point move over the switch, there is no lateral thrust on the movable rails corresponding to, or commensurate with, that which occurs during a trailing move, and what lateral thrust there is will be in the direction to permit the springs 43 to move the locking device 40 further toward the extreme position to which it is biased by the springs at the time the facing point move occurs.

It should be particularly pointed out that if the switch is moved from either extreme position to the full opposite extreme position when a train trails the switch, which is not normally the case, the total distance that the locking device 40 will be moved, due to its connection with the tie rod 8, will be less than the distance the locking device is moved when the switch is moved from either extreme position to the other by the hand lever 30, by an amount which is equal to the distance the end member 40b of the locking device can move on the plunger bolt 54 between the head of the plunger bolt and the collar 54^a; and the parts are so proportioned that the distance the end member 40b can move in the plunger bolt is equal to nearly half of the total movement of the locking device. It will be seen, therefore, that if a trailing train moves the switch from either extreme position to the other, the locking dog which was previously out of locking engagement with the lock rod will not be moved far enough to cause it to engage the lock rod, and as a result it is impossible for the switch to become locked in an extreme trailed position. In other words, with apparatus embodying my invention, the switch will only become locked when the position of the switch and the switch operating mechanism B correspond.

It will be noted that when the parts are in either of their two extreme positions, the reaction of the biasing springs 43 is transmitted through the rack teeth 27 and segment gear 33 to the hand throw lever 30, which reaction tends to raise this lever. This lever, however, is so designed that it has sufficient weight to resist and overcome this reaction. Furthermore, if it is undesirable for any reason to provide the lever 30 with sufficient weight to overcome the reaction of the springs 43, this lever may be held down by conventional lever latch stands in a well known manner.

The apparatus will usually also be provided with a circuit controller (not shown) including means for indicating when the locking device 40 is in its proper locking position for either facing point or trailing moves over the switch in both extreme positions of the switch, and means for indicating when the movable rail, which should be in close engagement with the associated fixed rail in either extreme position of the switch, is in proper engagement with such fixed rail. This circuit

controller is intended to be located in the casing 23 of the mechanism and may be of any suitable type. One type of circuit controller which can be used is shown and described in my copending application for Letters Patent of the United States Serial No. 665,914, filed on April 13, 1933, for Railway switch operating apparatus, the only change which need be made in this circuit controller being the substitution of the motion plate 63 shown attached to the upper face of the locking device 47 in Figs. 3 and 5, for the motion plate 63 shown in my copending application. The reason why it is desirable to substitute the motion plate 63 for the motion plate 63 is that it is essential, with the apparatus constructed as shown, to be sure that the linkage connecting the tie rod 8 with the locking device has not gotten out of adjustment and permitted the biasing springs 43 to drive the locking device 40 past its normal locking position in the normal position of the switch or past its reverse locking position in the reverse position of the switch, and the motion plate 63 is not properly shaped to give the desired indication, whereas the motion plate 63 is so shaped. With the motion plate 63 constructed as shown, when the locking device 40 occupies its normal locking position, a first spring biased roller, not shown, enters the notch b¹ and a second spring biased roller rides up onto the outer surface of the motion plate at point a⁵, and under these conditions, the normal indication contacts of the circuit controller are closed. When, however, the locking device is moved toward the right as viewed in Fig. 1, to withdraw the locking dog 47^a from the notches 49 in the lock rod L and unlock the switch, the first roller is forced out of notch b¹ and enters notch b², and the second roller moves off of the outer surface of the motion plate at point a⁵ and enters notch a², thus opening the normal indication contacts of the circuit controller in a manner which will be readily understood from an examination of my copending application. Likewise, if the locking device is moved past its normal locking position for any reason, the first roller will move out of notch b¹ and enter the notch b⁴ and the second roller will enter the notch a³. The notches b² and b⁴ are the same depth, and the notches a² and a³ are also the same depth, and it follows that with the motion plate constructed as shown, movement of the motion plate past its normal locking position will open the normal indication contacts in the same manner as these contacts are opened when the locking device is withdrawn from its normal locking position.

When the locking device 40 occupies its reverse position, the first roller rides up onto the outer surface of the motion plate at point b⁵ and the second roller enters notch a¹, thus closing the reverse indication contacts of the circuit controller. Movement of the locking device toward the left from its reverse locking position to unlock the switch will cause the first roller to move into notch b² and the second roller to move into notch a², while movement of the motion plate toward the right past its reverse locking position will cause the first roller to enter notch b³ and the second roller to enter notch a⁴. The notches b² and b³ are the same depth and the notches a² and a⁴ are also of the same depth, and it follows that movement of the motion plate away from its normal locking position in either direction will open the reverse indication contacts.

Referring now to Fig. 6 I have here shown another form of apparatus for locking a spring switch in either extreme position in such manner

that the switch will become unlocked when a train trails the switch by means mechanically actuated by the train. As here shown, the switch A, spring connecting rod C, and buffering device D are the same as is shown in Fig. 1. The spring rod 14 of the spring connecting rod C, however, instead of being connected with the switch operating arm 39 of the switch operating mechanism B in the manner shown in Fig. 1, is connected, by means of a pipe line 65, with a lever E¹ located in a tower T. The lever E¹ is movable between a normal position *n* in which it is shown in the drawings, and a reverse position *r* indicated by dotted lines in the drawings, and the parts are so proportioned that the switch will be moved to its normal or its reverse position according as the lever E¹ occupies its normal or its reverse position.

Associated with the switch A is a lock mechanism B¹ comprising two locking plungers 66^a and 66^b. As here shown, these locking plungers are mounted in fixed guideways 67^a and 67^b, respectively, and are biased to the right by means of springs 68^a and 68^b. One end of spring 68^a abuts against the guideway 67^a and the other end abuts against a collar 69^a which, in turn, abuts against a shoulder 70^a formed by a locking dog 71^a which is provided on the left-hand end of the locking plunger 66^a. In a similar manner, one end of spring 68^b abuts against the guideway 67^b and the other end abuts against a collar 69^b which, in turn, abuts against a shoulder 70^b formed by a locking dog 71^b which is provided on the left-hand end of the locking plunger 66^b. The right-hand end of the locking plunger 66^a is formed with an integral cross bar 72^a and provided in this cross bar on opposite sides of the plunger are two holes 73^a and 74^a which slidably receive two plunger bolts 75^a and 76^a, respectively. The right-hand end of the locking plunger 66^b is likewise formed with an integral cross bar 72^b having two holes 73^b and 74^b extending therethrough, which holes slidably receive two plunger bolts 75^b and 76^b. A T-crank lever 77 is pivotally supported at point 78, and one arm 77^a of this lever is operatively connected with the plunger bolt 75^a by means of a link 80^a, while the opposite arm 77^b of this lever is operatively connected with the plunger bolt 75^b by means of a link 80^b. The remaining arm 77^c of the lever 77 is operatively connected with the tie rod 8 by means of the operating rod 59 and switch basket 60. The plunger bolt 76^a is operatively connected, by means of a link 82^a, with one arm 81^a of a bell crank lever 81, and the plunger bolt 76^b is operatively connected, by means of a link 82^b, with one arm 83^a of a bell crank lever 83. The two levers 81 and 83 are pivotally supported at points 84 and 85, respectively, and the remaining arms 81^b and 83^b of these levers are each pivotally connected, by means of a pipe line 87, with a lever E² located in the tower T. The lever E² is movable between a normal position *n* and a reverse position *r* and is adapted to be interlocked with the lever E¹ in accordance with the customary practice in such manner that lever E¹ can not be moved from either position to the other position unless lever E² occupies its *n* position. The locking dogs 71^a and 71^b cooperate with notches 49¹ and 51¹ in a lock rod L¹, the notches 49¹ being so arranged that these notches will align with the locking dog 71^a when and only when the switch occupies its reverse position, and the notches 51¹ being so arranged that these notches will align with the

locking dog 71^b when and only when the switch occupies its normal position.

With the apparatus constructed as shown in Fig. 6, when the switch occupies its normal position, the lever E¹ occupies its normal position and the lever E² its reverse position, and under these conditions, the locking plunger 66^b is held, by means of the associated spring 68^b in its locking position in which the locking dog 71^b enters the notches 51¹ in the lock rod L¹; while the locking plunger 66^a is held by means of the plunger bolt 75^a and link 80^a in an unlocking position in which the locking dog 71^a is out of engagement with the notches 49¹ in the rock rod L¹. When it is desired to move the switch from its normal position to its reverse position, lever E² is first moved from its reverse position *r* to its normal position *n*, then lever E¹ is moved from its normal position *n* to its reverse position *r*, and finally lever E² is restored to its reverse position *r*. The movement of lever E² from its reverse position to its normal position acts through the pipe line 87 and associated linkage to move the locking plunger 66^b from its locking position to an unlocking position, thereby unlocking the switch, while the movement of lever E¹ from its normal position to its reverse position moves the movable rails of the switch from their normal positions to their reverse positions in the manner previously described. As the movable rails of the switch move to their reverse positions, the resultant upward movement of tie rod 8 rotates T-crank lever 77 in a counter-clockwise direction, as viewed in Fig. 6, to an extreme position opposite to that in which it is shown in the drawings, and as a result, when lever E² is finally restored to its reverse position, the biasing spring 68^a associated with the locking plunger 66^a moves the locking plunger 66^a to its locking position in which the locking dog 71^a enters the notches 49¹ in the lock rod L¹, thereby locking the switch in its reverse position, while the locking plunger 66^b is prevented from moving to its locking position by virtue of the plunger bolt 75^b and link 80^b, as will readily be understood by an inspection of the drawings.

In order to restore the switch to its normal position after it has been moved to its reverse position in the manner just described, lever E² is first moved from its normal position to its reverse position, then lever E¹ is moved from its reverse position to its normal position, and finally, lever E² is restored to its reverse position. The subsequent movements of the parts under these conditions is just the reverse of those described above and will be readily understood from an inspection of the drawings without further description.

When the switch occupies its normal position and a train trails the switch, the lateral bending of the movable rails which takes place before the closed point of these rails opens, moves the tie rod 8 upwardly in the same manner as was previously described in connection with Fig. 1, and this motion acts through the T-crank lever 77, link 80^b and plunger bolt 75^b to move the locking plunger 66^b from its locking position to its unlocking position, thereby unlocking the switch. The corresponding and opposite motion of the link 80^a and plunger bolt 75^a will allow the spring 68^a to move the locking plunger 66^a toward its locking position, and when the switch is in its extreme trailed position, the end of locking dog 71^a will be held in engagement with the side of lock rod L¹ by means of the associated spring 68^a. After the train has completely trailed the

switch, the movable rails of the switch will be restored to their normal positions by the spring connecting rod C, and this return movement will act through the tie rod 8, switch basket 60, and operating rod 59 to restore the T-crank lever 77 to its normal position in which it is shown in the drawings, thereby restoring the locking plunger 66^a to its unlocking position, and at the same time permitting the spring 68^b to return the locking plunger 66^b to its locking position, thus re-locking the switch in its normal position.

If, while the switch is being trailed from its normal position the movable rails of the switch were moved to their full reverse positions, the locking dog 71^a on locking plunger 66^a might snap into the notches 49¹ in lock rod L¹. However, this does not occur except under unusual circumstances because the movable rails are not forced over sufficiently far during trailing to bring the notches 49¹ in alignment with the locking dog 71^a.

If, when the switch occupies its reverse position and is locked in this position, a train trails the switch, the movable rails will become bent in much the same manner as when the switch occupies its normal position and a train trails the switch, but this bending will now be in the direction to move the tie rod 8 downwardly instead of upwardly. As a result, under these conditions, the T-crank lever 77 will be rotated in a clockwise direction and this rotation will act through the link 80^a and plunger bolt 75^a to move the locking plunger 66^a from its locking position to its unlocking position, thereby unlocking the switch. This rotation of the T-crank lever 77 will also permit the biasing spring 68^b to move the locking plunger 66^b a certain amount toward its locking position. After the switch becomes unlocked, the movable rails are forced over in the same manner as if no point lock were provided. When the trailing train has completely passed the switch, the movable rails are restored to their reverse positions by the spring connecting rod C in the usual manner, thereby restoring T-crank lever 77 to its reverse position, and hence permitting locking plunger 66^a to return to its locking position in which the locking dog 71^a re-enters the notches 49¹ in the lock rod L¹. When the locking plunger 66^a has been restored to its locking position, all parts are then restored to the positions which they occupied before the train started to trail the switch.

Although I have herein shown and described only two forms of railway switch operating apparatus embodying my invention, it is understood that various changes and modifications may be made therein within the scope of the appended claims without departing from the spirit and scope of my invention.

Having thus described my invention, what I claim is:

1. In combination with a railway switch, a spring connecting rod connected with the movable rails of said switch, manually operable means connected with said connecting rod for moving said switch between its two extreme positions, lock mechanism for said switch effective when said switch is moved to either extreme position for locking said switch in such extreme position for locking said switch in such extreme position, a tie rod connecting the movable rails of said switch at a point between the heel and the point of the switch, and means connecting said tie rod and said lock mechanism and effective when a train approaches said switch in a trailing direction in either extreme position of the switch for actuating said lock mechanism to unlock the switch until after the train has completely passed the switch.

2. In combination with a railway switch, a spring connecting rod connected with the movable rails of said switch, manually operable means connected with said connecting rod for moving said switch between its two extreme positions, lock mechanism for said switch effective when said switch is moved to either extreme position for locking said switch in such extreme position, a tie rod connecting the movable rails of said switch at a point between the heel and the point of the switch, and means for connecting said lock mechanism with said tie rod in such manner that when a train trails said switch the lateral bending of the movable rails which takes place before a sufficient force is developed at the points of the movable rails to overcome the opposing force of the spring in said spring connecting rod will actuate said lock mechanism to unlock said switch until after the train has completely passed the switch.

3. In combination, a railway switch, means for moving said switch between its two extreme positions, a first and a second locking dog, a lock rod secured to the movable rails of said switch and provided with a first notch which aligns with said first locking dog when and only when said switch occupies its normal position and with a second notch which aligns with said second locking dog when and only when said switch occupies its reverse position, means effective when said switch occupies its normal position for biasing said first locking dog to a position in which it enters said first notch, means effective when said switch occupies its reverse position for biasing said second locking dog to a position in which it enters said second notch, and means mechanically actuated by a train approaching said switch in a trailing direction in either extreme position of the switch for moving the dog which is then in the associated notch in said lock rod to a position in which it is withdrawn from the associated notch until after the train is completely past the switch.

4. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to its other extreme position will move said switch from its normal position to its reverse position and vice versa, a locking device reciprocably mounted in said casing and operatively connected with said motion plate by means including a spring in such manner that said locking device will be biased to one extreme position or another extreme position according as said motion plate is moved to its one extreme position or its other extreme position, a locking plunger secured to said locking device and provided with two locking dogs, a lock rod secured to the movable rails of said switch and extending into said casing and provided with one notch which is adapted to receive one of said locking dogs when the switch occupies its normal position and said locking device is moved toward its one extreme position and with another notch which is adapted to receive the other locking dog when the switch occupies its reverse position and said locking device is moved toward its other extreme position, and means mechanically ac-

1. In combination, a spring switch, means for moving said switch between its two extreme positions, lock mechanism effective when said switch is moved to either extreme position for locking said switch in such extreme position for facing point moves over the switch, a tie rod connected with the movable rails of said switch at a point between the heel and the point of the switch, and means connecting said tie rod and said lock mechanism and effective when a train approaches said switch in a trailing direction in either extreme position of the switch for actuating said lock mechanism to unlock the switch until after the train has completely passed the switch.

2. In combination with a railway switch, a spring connecting rod connected with the movable rails of said switch, manually operable means connected with said connecting rod for moving said switch between its two extreme positions, lock mechanism for said switch effective when said switch is moved to either extreme position for locking said switch in such extreme position, a tie rod connecting the movable rails of said switch at a point between the heel and the point of the switch, and means connecting said tie rod and said lock mechanism and effective when a train approaches said switch in a trailing direction in either extreme position of the switch for actuating said lock mechanism to unlock the switch until after the train has completely passed the switch.

3. In combination, a railway switch, means for moving said switch between its two extreme positions, a first and a second locking dog, a lock rod secured to the movable rails of said switch and provided with a first notch which aligns with said first locking dog when and only when said switch occupies its normal position and with a second notch which aligns with said second locking dog when and only when said switch occupies its reverse position, means effective when said switch occupies its normal position for biasing said first locking dog to a position in which it enters said first notch, means effective when said switch occupies its reverse position for biasing said second locking dog to a position in which it enters said second notch, and means mechanically actuated by a train approaching said switch in a trailing direction in either extreme position of the switch for moving the dog which is then in the associated notch in said lock rod to a position in which it is withdrawn from the associated notch until after the train is completely past the switch.

4. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to its other extreme position will move said switch from its normal position to its reverse position and vice versa, a locking device reciprocably mounted in said casing and operatively connected with said motion plate by means including a spring in such manner that said locking device will be biased to one extreme position or another extreme position according as said motion plate is moved to its one extreme position or its other extreme position, a locking plunger secured to said locking device and provided with two locking dogs, a lock rod secured to the movable rails of said switch and extending into said casing and provided with one notch which is adapted to receive one of said locking dogs when the switch occupies its normal position and said locking device is moved toward its one extreme position and with another notch which is adapted to receive the other locking dog when the switch occupies its reverse position and said locking device is moved toward its other extreme position, and means mechanically ac-

tuated by the wheels of a train when a train trails the switch in either extreme position of the switch for actuating said locking device to withdraw the locking dog which is then in the associated notch in the lock rod from the associated notch to unlock the switch until after the train has completely passed the switch.

5. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to its other extreme position will move said switch from its normal position to its reverse position and vice-versa, a locking device reciprocably mounted in said casing and operatively connected with said motion plate by means including a spring in such manner that said locking device will be biased to one extreme position or another extreme position according as said motion plate is moved to its one extreme position of its other extreme position, a locking plunger secured to said locking device and provided with two locking dogs, a lock rod secured to the movable rails of said switch and extending into said casing and provided with one notch which is adapted to receive one of said locking dogs when the switch occupies its normal position and said locking device is moved toward its one extreme position and with another notch which is adapted to receive the other locking dog when the switch occupies its reverse position and said locking device is moved toward its other extreme position, a tie rod connecting the movable rails of the switch at a point between the heel and the point of the switch, and linkage connecting said tie rod and said locking device and effective when a train trails the switch in either extreme position of the switch for actuating said locking device to withdraw the locking dog which is then in the associated notch in the lock rod from the associated notch to unlock the switch until after the train has completely passed the switch.

6. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to its other extreme position will move said switch from its normal position to its reverse position and vice-versa, a locking device reciprocably mounted in said casing and operatively connected with said motion plate by means including a spring in such manner that said locking device will be biased to one extreme position or another extreme position according as said motion plate is moved to its one extreme position or its other extreme position, a locking plunger secured to said locking device and provided with two locking dogs, a lock rod secured to the movable rails of said switch and extending into said casing and provided with one notch which is adapted to receive one of said locking dogs when and only when the switch occupies its normal position to lock the switch in its normal position and with another notch which

is adapted to receive the other locking dog when and only when the switch occupies its reverse position to lock the switch in its reverse position, the parts being so proportioned that when said one locking dog is within said one notch it will move past a desired locking position if it is then permitted to move to its one extreme position and that when said other locking dog is within said other notch it will move past a desired locking position if it is then permitted to move to its other extreme position, a tie rod connecting the movable rails of said switch at a point between the heel and the point of the switch, linkage connecting said locking device and said tie rod so constructed that when said switch occupies its normal position said linkage will prevent said locking device from being moved by said spring past the desired locking position in said one notch and that when said switch occupies its normal position and a train trails the switch said linkage will move said locking device to a position in which said one locking dog is withdrawn from said one notch until after the train is completely past the switch, said linkage being further so constructed that when said switch occupies its reverse position said linkage will prevent said locking device from being moved by said spring past the desired locking position in said other notch and that when said switch occupies its reverse position and a train trails the switch said linkage will move said locking device to a position in which said other locking dog is withdrawn from said other notch until after the train is completely past the switch, and means secured to said locking plunger for actuating a circuit controller to indicate when said two locking dogs occupy the desired locking positions.

7. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with the movable rails of said switch in such manner that movement of said motion plate from its one extreme position to its other extreme position will move said switch from its normal position to its reverse position and vice-versa, a lock rod secured to the movable rails of said switch and extending into said casing and provided with two notches, a locking device slidably mounted in said casing above said motion plate, said locking device comprising two spaced end members connected together by two spaced parallel bolt members, one of said end members being provided with a hole, a locking plunger secured to the other end member and provided with two locking dogs one of which is adapted to enter one of said notches in said lock rod when and only when the switch occupies its normal position and the other of which is adapted to enter the other notch in said lock rod when and only when said switch occupies its reverse position, two pairs of lugs on said motion plate, the one pair being provided with aligned holes which receive one of said bolt members with considerable clearance and the other pair of lugs being provided with aligned holes which receive the other bolt member with considerable clearance, two springs one surrounding each of said bolt members, four spring sockets one slidably mounted in the hole in each of said lugs and each provided at one end with an inwardly extending annular flange which engages

an outwardly extending annular flange which cooperates with the associated lug, each said spring socket being free to slide on the associated bolt member, a plunger bolt extending through the 5 hole in said one end member with some clearance and provided at its inner end with a head which is larger than said hole, a collar secured to said plunger bolt on the opposite side of said end member from said head a spaced distance from said 10 head, a tie rod connecting the movable rails of said switch at a point approximately midway between the heel and the point of the switch, and linkage connecting said tie rod and said plunger bolt, the parts being so proportioned that when 15 said motion plate occupies its one extreme position said locking device is biased by said springs to a position in which said one locking dog is moved past a desired locking position within said one notch but is prevented by engagement of said 20 one end member with the head of said plunger bolt from moving past the position in which said one locking dog occupies the desired locking position and that when the switch occupies its normal position and a train trails the switch said linkage will move said locking device from the 25 position in which said one locking dog occupies the desired locking position to a position in which said one locking dog is withdrawn from said one notch, the parts being further so proportioned 30 that when said switch occupies its other extreme position said locking device is biased by said springs to a position in which said other locking dog is moved past a desired locking position within said other notch but is prevented by engagement of said one end member with said collar from moving past the position in which said other locking dog occupies the desired locking position and that when the switch occupies its reverse 35 position and a train trails the switch said linkage will act through said collar to move said locking device from the position in which said other locking dog occupies the desired locking position to a position in which said other locking dog is withdrawn from said other notch. 40

10. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with the movable rails of said switch in such manner that movement of said motion plate from its one extreme position 45 to its other extreme position will move said switch from its normal position to its reverse position and vice-versa, a lock rod secured to the movable rails of said switch and extending into said casing and provided with two notches, a locking device 50 vice slidably mounted in said casing above said motion plate, said locking device comprising two spaced end members connected together by two spaced parallel bolt members, one of said end members being provided with a hole, a locking plunger secured to the other end member and provided with two locking dogs one of which is adapted to enter one of said notches in said lock rod when and only when the switch occupies its 55 normal position and the other of which is adapted to enter the other notch in said lock rod when and only when said switch occupies its reverse position, two pairs of lugs on said motion plate, the one pair being provided with aligned holes which receive one of said bolt members with considerable clearance and the other pair of lugs be- 60

ing provided with aligned holes which receive the other bolt member with considerable clearance, two springs one surrounding each of said bolt members, four spring sockets one slidably mounted in each of said holes and each provided at one end with an inwardly extending annular flange which engages the adjacent end of the spring on the associated bolt member and at the other end with an outwardly extending annular flange which cooperates with the associated lug, 5 each said spring socket being free to slide on the associated bolt member, a plunger bolt extending through the hole in said one end member with some clearance and provided at its inner end with a head which is larger than said hole, a collar secured to said plunger bolt on the opposite side of said end member from said head, a tie rod connecting the movable rails of said switch at a point approximately midway between the heel and the point of the switch, and linkage connecting said tie rod and said plunger bolt, the parts being so proportioned that when said motion plate occupies its one extreme position said locking device is biased by said springs to a position in which said one locking dog is moved past a desired locking position within said one notch but is prevented by engagement of said one end member with the head of said plunger bolt from moving past the desired locking position and that when the switch occupies its normal position and a train trails the switch said linkage will move said locking device from the position in which said one locking dog occupies the desired locking position to a position in which said one locking dog is withdrawn from said one notch, the parts being further so proportioned that when said switch occupies its other extreme position said locking device is biased by said springs to a position in which said other locking dog is moved past a desired locking position within said other notch but is prevented by engagement of said one end member with said collar from moving past the desired locking position and that when the switch occupies its reverse position and a train trails the switch said linkage will act through said collar to move said locking device from the position in which said other locking dog occupies the desired locking position to a position in which said other locking dog is withdrawn from said other notch, the parts being still further so proportioned that when said motion plate is moved from either extreme position to the other extreme position said lugs will cooperate with said spring sockets to exert a force on said motion plate through the medium of said springs in such manner that said locking device will be moved to a position in which both locking dogs are out of engagement with the associated notches in said lock rod before the movable rails start to move. 65

11. In combination, a railway switch, means including a spring connecting rod for moving said switch between its two extreme positions, two locking plungers each biased to a locking position and each provided at one end with a locking dog, a lock rod secured to the movable rails of said switch and provided with two notches, one of which receives the one locking dog when the switch occupies its normal position and the one locking plunger occupies its locking position and the other of which receives the other locking dog when the switch occupies its reverse position and the other locking plunger occupies its locking position, a tie rod connecting the movable rails of the switch at a point approximately midway be- 70

75

- between the heel and the point of the switch, means for connecting both said locking plungers with said tie rod in such manner that said one or said other locking plunger will be prevented from moving to its locking position according as said switch occupies its reverse or its normal position and that when said switch occupies either extreme position and a train trails the switch the locking plunger which then occupies its locking position will be moved to an unlocking position, and other means for moving both said plungers from their locking positions to their unlocking positions.
12. In combination, a railway switch, a first manually operable lever movable between a normal and a reverse position, means including a spring connecting rod and a pipe line for connecting said first lever with the movable rails of said switch in such manner that said switch will be moved to its normal or its reverse position according as said lever occupies its normal or its reverse position, a first locking plunger biased to a locking position and provided with a first locking dog, a second locking plunger biased to a locking position and provided with a second locking dog, a lock rod secured to the movable rails of said switch to move therewith and provided with a first notch which is adapted to receive said first locking dog when said switch occupies its normal position and said first locking plunger occupies its locking position and with a second notch which is adapted to receive said second locking dog when said switch occupies its locking position and said second locking plunger occupies its locking position, a first cross bar formed on said first locking plunger and provided with two holes, a second cross bar formed on said second locking plunger and provided with two holes, a first plunger bolt slidably mounted in one of the holes in said first cross bar, a second plunger bolt slidably mounted in the other hole in said first cross bar, a third plunger bolt slidably mounted in one hole in said second cross bar, a fourth plunger bolt slidably mounted in the other hole in said second cross bar, a pivoted T-crank lever, means including a first link for connecting said first plunger bolt with one arm of said T-crank lever, means including a second link for connecting said third plunger bolt with the arm of said T-crank lever opposite to said one arm, a tie rod connecting the movable rails of the switch at a point approximately midway between the heel and the point of the switch, means for connecting said tie rod with the remaining arm of said T-crank lever in such manner that said T-crank lever will be rotated to one extreme position or another extreme position according as said switch is moved to its normal or its reverse position, the parts being so proportioned that when said T-crank lever occupies said one extreme position said second locking plunger will be prevented from moving to its locking position and that when said T-crank lever occupies its other extreme position said first locking plunger will be prevented from moving to its locking position, two pivoted bell crank levers, means for operatively connecting one arm of the one bell crank lever with said second plunger bolt, means for operatively connecting one arm of the other bell crank lever with said fourth plunger bolt, means for pivotally connecting the remaining arms of said two bell crank levers with a pipe line in such manner that said movement of said pipe line will simultaneously rotate both bell crank levers in the same direction, and a second manually operable lever movable between a normal and a reverse position, said second lever being connected with said pipe line in such manner that when said second manually operable lever is rotated to its reverse position said locking plungers will both be moved to unlocking positions.
13. In combination, a railway switch, an operating mechanism for said switch comprising a casing, a motion plate mounted in said casing for reciprocation between two extreme positions, means for reciprocating said motion plate between its two extreme positions, means including a spring connecting rod for operatively connecting said motion plate with said movable rails in such manner that movement of said motion plate from its one extreme position to its other extreme position will move said switch from its normal position to its reverse position and vice-versa, a locking device reciprocably mounted in said casing and operatively connected with said motion plate by means including a spring in such manner that said locking device will be biased to one extreme position or another extreme position according as said motion plate is moved to its one extreme position or its other extreme position, a locking plunger secured to said locking device and provided with two locking dogs, a lock rod secured to the movable rails of said switch and extending into said casing and provided with one notch which is adapted to receive one of said locking dogs when and only when the switch occupies its normal position to lock the switch in its normal position and with another notch which is adapted to receive the other locking dog when and only when the switch occupies its reverse position to lock the switch in its reverse position, the parts being so proportioned that when said one locking dog is within said one notch it will move past a desired locking position if it is then permitted to move to its one extreme position and that when said other locking dog is within said other notch it will move past a desired locking position if it is then permitted to move to its other extreme position, a tie rod connecting the movable rails of said switch at a point between the heel and the point of the switch, linkage connecting said locking device and said tie rod so constructed that when said switch occupies its normal position said linkage will prevent said locking device from being moved by said spring past the desired locking position in said one notch and that when said switch occupies its normal position and a train trails the switch said linkage will move said locking device to a position in which both locking dogs are out of engagement with the associated notches in said lock rod until after the train is completely past the switch, said linkage being further so constructed that when said switch occupies its reverse position said linkage will prevent said locking device from being moved by said spring past the desired locking position in said other notch and that when said switch occupies its reverse position and a train trails the switch said linkage will move said locking device to a position in which both said locking dogs are out of engagement with the associated notches in said lock rod.
14. In combination, a railway switch, manually operable switch actuating means for moving said switch to its two extreme positions, biasing means effective for biasing said switch to the extreme position to which it is moved by said manually operable means, lock mechanism effective for normally locking said switch in the extreme position.

- tion to which it is biased, and means mechanically actuated by a train approaching said switch in a trailing direction when said switch occupies either extreme position for actuating said lock mechanism to unlock said switch until the train is completely past the switch, said lock mechanism being effective to relock said switch automatically after it has been trailed as soon as said switch has been restored to its original position by said biasing means.
- 10 15. In combination, a railway switch, switch actuating means for moving said switch to its two extreme positions, lock mechanism effective for locking the switch in either extreme position to which it is moved by said switch actuating means for facing point moves over the switch, a tie rod connected with the movable rails of said switch between the heel and the point of the switch, means connecting said tie rod and said lock mechanism and effective when a train approaches said switch in a trailing direction in either extreme position of the switch for actuating said lock mechanism to unlock the switch until the train has passed the switch, and means effective after a train has trailed the switch for

restoring the switch to its original position, said lock mechanism being effective to relock said switch for facing point moves over said switch as soon as said switch has been restored to its original position by said restoring means.

16. In combination, a railway switch, switch actuating means for moving said switch to its two extreme positions, lock mechanism effective for locking the switch in either extreme position to which it is moved by said switch actuating means for facing point moves over the switch, means mechanically actuated by a train approaching said switch in a trailing direction when said switch occupies either extreme position for actuating said lock mechanism to unlock said switch until the train is completely past the switch, and means effective after a train has trailed the switch for restoring the switch to its original position, said lock mechanism being effective to automatically relock said switch for facing point moves over said switch as soon as said switch has been restored to its original position by said restoring means.

HERBERT L. BONE.
